PAGE 2

Fig. 3.

FIG. 1 is a perspective view taken from one side and slightly above a swather, showing our new design;

FIG. 2 is a side elevational view taken from the other side thereof;

FIG. 3 is a perspective view thereof, with the front platform in a raised position; and

FIG. 4 is a front elevational view of a swather. The dominant features of our design reside in the full line portions.

We claim:

The ornamental design for a swather, as shown and described.
